UNITED STATES PATENT OFFICE.

CLYDE N. FRIZ, OF CHARLESTON, SOUTH CAROLINA.

MUSIC-LEAF TURNER.

SPECIFICATION forming part of Letters Patent No. 651,110, dated June 5, 1900.

Application filed June 28, 1899. Serial No. 722,112. (No model.)

To all whom it may concern:

Be it known that I, CLYDE N. FRIZ, a citizen of the United States, residing at the city of Charleston, in the county of Charleston and State of South Carolina, have invented certain new and useful Improvements in Music-Leaf Turners, of which the following is a full, clear, and exact description, reference being had to the accompanying drawings, forming part of this specification.

My invention relates to an improved music-leaf turner especially designed for use on pianos and organs, but also suitable for music-stands, and intended to be made adjustable to the ledges of music-racks as now found on the various makes of pianos and organs.

The object of my invention is to provide a music-leaf turner that will be absolutely infallible in the action of the escapement device controlling the leaf-turning arms and one that will give a minimum amount of trouble in attaching to the instrument and in arranging the music.

My invention consists in features of novelty hereinafter fully described, and pointed out in the claims.

Figure I is a perspective view showing my improved leaf-turner with part of the leaf-turning arms set in position for use and one arm tripped. Fig. II is a vertical longitudinal sectional view taken on the line II II, Fig. III. Fig. III is a vertical transverse sectional view taken on the line III III, Fig. II. Fig. IV is a horizontal sectional view taken on the line IV IV, Fig. II. Fig. V is an enlarged detail perspective view of portions of one of the leaf-turning arms and the coinciding portion of the finger-lever whereby they are tripped. Fig. VI is a detail view showing in section a portion of the top of the turner-case and in edge view the push-rod carried by the music-holding clamp. Fig. VII is a detail view of one of the adjustable clamping members by which the turner is secured to a music-rack.

1 designates the case in which the operating parts of the leaf-turner are mounted and upon which the music-holding clamp is supported. This case is illustrated as closed at its rear side and is provided at its front side with a horizontal slot 2, extending from end to end of the case. The case 1 is designed to

be attached to the ledge of a music-rack of a piano or organ by angle members 3, connected to the case. The members are provided with spring-arms 4 and 5 at their respective ends, 55 preferably covered with a padding 6 of rubber, felt, or other suitable material. The spring-arms 4 and 5 overlap and are adapted to bear upon opposite sides of the ledge portion of a music-rack, and the spring-arm 5 is 60 adapted to be sprung toward the spring-arm 4 by a set-screw 7, turning in the member and case, for the purpose of adjusting the space between the spring-arms to accommodate them to the thickness of the portion of the 65 music-rack which they embrace. The spring-arms are provided with coinciding apertures (see Figs. I and VII) through which a screw-driver may be inserted to move the screw 7 at will. The members 3 may be attached to 70 the under side of the case or the rear thereof, according to the formation of the rack to which they are applied.

The music to be held and turned is placed above the case 1 and in the rear of a vertical 75 post 8, extending downwardly to the bottom of said case. In the rear of the post 8 is a clamp-bar 9, that is backed by a spring 10, secured to an upright 11. The spring 10 serves to hold the clamp-bar 9 forwardly to 80 retain the music sheet or book between said clamp-bar and post 8. The lower end of the clamp-bar 9 extends through a slot 1^b in the top of the case 1, (see Fig. VI,) from which a push-rod 12 extends forwardly through a 85 slot in the front of the case and is provided with a finger-piece 13 and a notch 14, adapted to receive the wall of the case when the push-rod is pressed inwardly, and thereby hold the clamp-bar 9 in retracted position. When the 90 push-rod is released, the spring 10 carries the clamp-bar forward against the music sheet or book placed back of the post 8.

15 designates a cylinder seated vertically between the top and bottom of the case 1. 95 This cylinder is provided with a series of vertical perforations 16, either of which is adapted to receive the post 8, which, as stated, extends through the case to its bottom.

17 designates the leaf-turning arms, the inner ends of which are of disk form and encircle the cylinder 15. Attached at one end

to each arm is an individual spring 18, each one of which laps around and is connected at its opposite end to the cylinder 15. The tension of the springs 18 is rendered of the desired degree according to the position in which the cylinder 15 is held with relation thereto by the post 8 extending therethrough in one of the apertures 16 to maintain the cylinder in fixed position, the cylinder being 5 adjustable on the post and held immovably. The inner end of each turning-arm is separated from that of the arm adjacent thereto by fingers 19. (See Fig. IV.) The outer end of each leaf-turning arm is provided with an 10 upright finger 20, and pivoted to a bent extension 17^a on each arm is a clamp-piece 21, provided with tongues 22 and 23. The inner tongue 22 is adapted to engage the lower edge of the arm 17 to prevent the clamp-piece 21 15 from extending too far down. By referring to Fig. IV it will be seen that the outer ends of the leaf-turning arms, to which the clamp-pieces 21 are pivoted, are bent at an angle to the main bodies of the arms, thereby causing 20 the bodies of the clamp-pieces 21 to receive an inclined movement with relation to the plane of the leaf-turning arms as they come in contact with and lie flatly against the upright fingers 20, holding a sheet or leaf of 25 music between the two parts. In other words, by reason of the outer ends or extensions 17^c of the arms 17 being bent at an angle to the main portion of the arms the clamp-pieces 21, which are pivoted to these extensions, are 30 also disposed at an angle to the upright fingers 20, so that when said clamp-pieces are swung on their pivots their first approaching edges will become disposed at an angle to the fingers 20, and as they are pressed against 35 the fingers 20 the clamp-pieces will be caused to twist toward a parallel with the upright fingers to clamp the music-sheet between the two parts. The more force used in pushing the clamp-piece 21 into position the more 40 tightly, as a consequence, will the sheet or 45 leaf be gripped.

The leaf-turning arms are adapted to be held against the tension of the springs 18 by the following-described parts: 24 designates 50 a finger-lever projecting through an elongated pocket 25 in the case 1 (see Fig. I) and provided with pivotal connection to a socket-piece 26 within the case, said socket-piece being hinged to a bracket 27, projecting from 55 the case on its interior. The finger-lever 24 is arranged to partake of a lateral swinging movement in the clamp 21 and is adapted to be moved vertically by the socket-piece 26, pivoting in the bracket 27. 60 Connected to the finger-lever is a spring 28, that also connects to the case 1, (see Fig. II,) the said spring being designed to exert an upward pull on the finger-lever. On the finger-lever 24 is a stop-piece 29, and located 65 a short distance from the said stop-piece and also on the finger-lever is an upright hook 30. Each of the turning-arms is provided with a

recess 17^a in its under side and provided with a tongue 17^b, having a beveled upper edge extending part way across said recess, but 70 leaving a space between its end and the opposing end of the recess. When the leaf-turning arms are thrown from the left into the position seen in Figs. II, III, and IV, they each come in contact with the stop-piece 29 75 and riding against the inclined edge of said stop-piece force the finger-lever 24 to the left and pass behind said stop-piece, and the spring 28 immediately returns the finger-lever to its normal position, as seen in the drawings. The next arm being brought around 80 is carried into the same position as the first past the stop-piece 29, and the first entering arm is moved past the upright hook 30, so that it is engaged thereby. The turning-arms 85 may thus be swung into position under tension for the reception of the music-leaves being moved either one at a time or collectively, and when in such position all but the foremost one will lie back of the hook 30, while 90 the foremost one will rest between said hook and the stop 29. When the finger-lever is depressed, the stop 29 is carried downward, moving it out of the way of the tongue 17^b of the turning-lever, thereby freeing the foremost lever and permitting its escape to turn and carry a music-leaf. At the same time the hook 30 moves with the finger-lever and catches the next succeeding turning-arm to hold it from turning until the finger-lever has 95 been again elevated by the impulse of the spring 28, on which occurrence a second turning-arm is released to come in contact with the stop-piece 29 to act in the same manner as the first on the depression of the finger-lever, and so on throughout the series of arms as they are consecutively released. It will be observed that the spring 28 is so placed as to give a quick and vigorous action 100 both to the right and upwardly with an easy 105 touch and that the case is provided with a tongue 1^a, partially inclosing the pocket 25, which arrangement serves as a stop for the finger-lever in either vertical or horizontal movement. It will also be seen that the 110 pocket 25 is inclined at its lower edge, so that in case the finger-lever fails to assume its proper position the arm-retaining parts are carried to the right, so that the finger-lever 115 24 will rise into proper position to engage the tongues 17^b of the leaf-turning arms, the inclined edge of the pocket forcing the lever to the right as it descends and putting it into proper position for its elevation by the action 120 of the spring 28. 125

I claim as my invention—

1. In a leaf-turner, the combination of a case, leaf-turning arms, arranged to operate therein, a clamp comprising right-angled members secured by the inner member to the case 130 and having spring-arms provided with coinciding perforations extending from the ends of the members, and overlapping beneath the inner member, and a set-screw, working in

the inner member, and against which the free end of the inner spring bears; the head of the screw being in line with the perforations; substantially as and for the purpose set forth.

5 2. In a leaf-turner, the combination of a case, leaf-turning arms arranged to operate therein, a post projecting from said case, a clamp-bar located in proximity to said post, a spring bearing against said clamp-bar, and 10 a push-rod by which said clamp-bar may be moved, substantially as described.

3. In a leaf-turner, the combination of a case, a cylinder having a series of perforations parallel to its axis and mounted in said case, a post extending through one of the perforations and adapted to hold said cylinder in an adjusted position, leaf-turning arms surrounding said cylinder, and springs lapping around the cylinder and connecting said 15 arms and said cylinder, substantially as described.

4. In a leaf-turner, the combination of a case, leaf-turning arms, each arm having a recess in its under side and a tongue formed 20 with a beveled upper edge and extending part way across the recess leaving a space between its end and the opposite end of the recess, a spring-controlled finger-lever, a stop having an inclined edge and carried by said finger- 25 lever, and a hook carried by said finger-lever and adapted to engage said leaf-turning arms 30

when said finger-lever is depressed, substantially as described.

5. In a leaf-turner, the combination of a case, spring-controlled leaf-turning arms, a 35 spring-controlled finger-lever, a socket-piece to which said lever is pivoted to move laterally, said socket-piece being pivoted to said case to move vertically; and a stop and hook carried by said finger-lever adapted to engage 40 said turning-arms to control their release, substantially as described.

6. In a leaf-turner, the combination of a case, spring-actuated leaf-turning arms each having a bent extension and mounted therein, 45 upright fingers carried by said arms, swinging clamp-pieces pivoted to said bent extensions of said arms, said clamp-pieces being adapted to be moved to and from said upright fingers at an inclination to the latter and provided with tongues adapted to bear against said arms and limit the outward movement of the clamp-pieces, and also with tongues adapted to swing said clamp-pieces into close contact with said fingers for the purpose of 50 55 clamping the sheet or leaf, substantially as described.
